UNITED STATES PATENT OFFICE

PAUL HALLER, OF LAWRENCE, KANSAS

DESIGN FOR AN AUTOMOBILE RADIATOR ORNAMENT

Application filed May 5, 1931. Serial No. 39,722. Term of patent 7 years.

To all whom it may concern:

Be it known that I, PAUL HALLER, a citizen of the United States, residing at Lawrence, in the county of Douglas and State of Kansas, have invented a new, original, and ornamental Design for an Automobile Radiator Ornament, of which the following is a specification, reference being had to the accompanying drawings, forming part thereof.

Figure 1 is a side elevational view of an automobile radiator ornament showing my new design.

Figure 2 is a front perspective view of the same on a reduced scale.

I claim:

The ornamental design for an automobile radiator ornament substantially as shown.

PAUL HALLER.
